UNITED STATES PATENT OFFICE

1,934,995

COTTON BALE BUCKLE AND TIE

Tom Owen, Butler, Ala.

Application April 7, 1933. Serial No. 664,961

2 Claims. (Cl. 24—23)

The present invention relates to new and useful improvements in cotton bales and ties and has for some of its objects to provide, in a manner as hereinafter set forth, a device of this character which will be simple in construction, strong, durable, highly efficient and reliable in use, compact, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

15 Figure 1 is a perspective view of a bale of cotton, showing a plurality of buckles and ties in accordance with the present invention thereon.

Figure 2 is a view in vertical transverse section through the bale showing, in vertical section, a buckle and tie in accordance with the present invention thereon.

Figure 3 is a detail view in perspective of the end portions of the band.

Figure 4 is a detail view in perspective of the buckle.

Figure 5 is a view in vertical section through the buckle.

Figure 6 is a horizontal sectional view, taken substantially on the line 6—6 of Figure 1.

30 Referring now to the drawings in detail, it will be seen that the reference numeral 1 designates a bale of cotton around which extends a plurality of flat, metallic bands 2. The bands 2 are of sufficient length to permit the end portions thereof to be brought into overlapping relationship, as illustrated to advantage in Figures 1 and 2 of the drawings. One end portion of each band 2 is provided with a series of spaced eyes 3 while the other end portion of each of said bands 2 is 40 provided with a single eye 4, (see Figure 3).

The bands 2 are secured tightly around the bale 1 through the medium of buckles which are designated generally by the reference numeral 5. Each buckle 5 is formed from a single piece of 45 suitable metal and comprises a flat plate 6 having right angularly extending end portions 7 projecting in opposite directions therefrom. Immediately adjacent the plate 6, each of the end portions 7 is provided with a slot 8. The slots 8 50 slidably receive the overlapping end portions of the bands 2.

Struck from the plate 6 in a manner to project on opposite sides of said plate and adjacent the end portions 7 are oppositely extending tongues

55 9. As best seen in Figure 5 of the drawings, the

tongues 9 and the adjacent end portions 7 are on opposite sides of the plate 6.

In use, the end portions of the bands 2 are inserted in the slots 8 of the buckles 5 and the outer tongues 9 of said buckles are engaged in the single eyes 4 in one end portion of the bands 2. Then, when the bands are tightened around the bale, the innermost tongues 9 of the buckles 5 are engaged in one of the eyes 3, thus securely tying the ends of the bands together. As will be apparent, the inner tongues of the buckles are selectively engageable in the eyes 3.

It is believed that the many advantages of a buckle and tie in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:

1. A buckle comprising a plate including right angularly extending end portions projecting in opposite directions, said end portions having slots therein and oppositely extending tongues projecting from opposite sides of the plate in spaced, opposed relation to the end portions of said plate, the free portions of said tongues extending toward the angularly directed end portions of said plate and arranged in spaced parallel relation to said plate.

2. A buckle being formed from a single piece of metal and comprising a substantially flat plate including right angularly extending end portions projecting in opposite directions therefrom, the end portions of the plate having slots therein immediately adjacent said plate and oppositely extending tongues struck from the plate and projecting from opposite sides thereof in spaced, opposed relation to the end portions of the plate, the free portions of said tongues extending toward the angularly extending end portions of said plate and arranged in spaced parallel relation to said plate.

TOM OWEN.
